PORTRABLE CASHIER UNIT

Delmare D. Rhoads, 3230 South Carolina St.,
Fort Wayne, Ind.

Filed June 9, 1958, Ser. No. 51,239

Term of patent 14 years

(Cl. D14—3)

FIG.1

FIG.3

FIG.2

FIG.4

Figure 1 is a perspective view of a portable cashier unit showing my new design.

Figure 2 is a top view of the portable cashier unit shown in Figure 1.

Figure 3 is a side elevational view of the portable cashier unit shown in Figure 1. The side opposite that shown is substantially the same as the side shown in Figure 3.

Figure 4 is a rear elevational view of the portable cashier unit illustrated in Figure 1.

The front not shown is plain aside from the shelf and two supporting brackets.

I claim:

The ornamental design for a portable cashier unit, substantially as shown and described.
